UNITED STATES PATENT OFFICE.

RICHARD RALPH BLOSS, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA.

DERRICK-FITTING.

1,400,408.

Specification of Letters Patent. Patented Dec. 13, 1921.

Application filed October 2, 1920. Serial No. 414,241.

To all whom it may concern:

Be it known that I, RICHARD R. BLOSS, a citizen of the United States, residing at Parkersburg, in the county of Wood and State 5 of West Virginia, have invented certain new and useful Improvements in Derrick-Fittings, of which the following is a specification.

This invention relates to derrick fittings, 10 and it comprises a substantially cylindrical body portion adapted to receive an upper and lower leg section, means for securing the horizontal girths to said fitting, and means for securing the diagonal braces 15 thereto, said means comprising eccentric blocks having openings therein for the reception of the ends of the braces whereby the braces may be tightened by the operation of said eccentrics.

In the construction and use of derrick fittings, there are certain essentials which must be considered in order to produce a fitting that will meet with the approval of the trade. A derrick fitting must be simple to erect 20 and it must be so arranged that the rig builder is not depended upon to get the structure true. It is, therefore, advisable that the use of adjustable turn buckles and similar structures be eliminated and that the 25 various parts of the derrick be cut to the proper length with the holes properly placed to insure a symmetrical structure. Where the adjustment of the parts is left to the rig builder, it frequently happens that the derrick 30 is unsymmetrical when assembled and therefore weak.

It is also desirable to provide a derrick fitting which permits speed in erecting and disassembling. The use of bolts passing 40 through the leg sections, girths or braces which have to be entirely removed to disassemble the derrick, is objectionable because of the time consumed in such operation.

In the present invention, I have provided 45 a derrick fitting wherein the range of adjustment of the diagonal braces is limited and wherein all parts may be cut the proper size and openings properly placed to insure a symmetrical construction when the derrick 50 is assembled.

I have further provided a derrick fitting wherein no bolts have to be entirely removed to disassemble the derrick. In one form of the invention, the leg sections and girths are

received in sockets and no bolts whatever 55 are used. In other forms of the invention, wherein bolts and nuts are employed, they are so arranged that the derrick may be disassembled by merely loosening the nuts.

In the accompanying drawings, I have 60 shown several advantageous embodiments of the invention. In this showing,

Figure 1 is a side elevation of one form of the derrick fitting showing the ends of the leg sections, girth and braces. 65

Fig. 2 is a similar view at right angles to Fig. 1.

Fig. 3 is a horizontal sectional view on the line 3—3 of Fig. 1.

Fig. 4 is a detail view of the fastening 70 means for the diagonal brace.

Fig. 5 is a side elevation of another form of the invention.

Fig. 6 is a vertical sectional view through the body portion of the fitting showing the 75 leg sections in position.

Fig. 7 is a horizontal sectional view on the line 7—7 of Fig. 5.

Fig. 8 is a side elevation of another form 80 of the invention.

Fig. 9 is a similar view at right angles thereto.

Fig. 10 is a horizontal sectional view on the line 10—10 of Fig. 8.

Fig. 11 is a detail perspective view of 85 the body portion of the fitting showing the means for retaining the leg sections in position, and

Fig. 12 is a sectional view on the line 12—12 of Fig. 9. 90

Referring to Figs. 1 to 4 of the drawings, the reference numeral 1 designates the body portion of the fitting which is adapted to receive upper and lower leg sections 2 and 3. As shown, the cylindrical section 1 95 is provided with a longitudinal slit and pairs of ears 4 and 5 are arranged on each side of the opening. These ears are provided with aligned openings adapted to receive a bolt 6 to permit tightening and loosening of the body portion when the leg sections are being put in position or removed. The bolts are provided with nuts 7 as shown.

A pair of plates 8 and 9 are secured to the body portion at substantially right angles 100 to each other and these plates are provided with cylindrical sockets 10 for the reception of the horizontal girths 11. The lower

portions of the plates are provided with openings adapted to receive the upper ends of diagonal braces 12. As shown, the ends of the braces are offset as at 13 and passed through the openings. The offset end of the brace is provided with openings for the reception of a cotter pin 14 whereby the end of the brace is secured in position.

The upper portions of the plates 8 and 9 are provided with means for receiving the lower ends of the diagonal braces extending to the next fittings and means are provided for adjusting the braces whereby the derrick may be first assembled and the braces then tightened to secure all the parts in proper position. As stated, the adjustment is within a limited range and the parts are so constructed that when all the adjustments have been made, a symmetrical construction will be obtained. As shown, the plates are provided with circular openings adapted to receive blocks 15. These blocks are provided with operating handles 16 whereby they may be rotated. The end 17 of the handle is offset and adapted to lie adjacent the brace when in assembled position. A ring 18 is arranged on the brace and is adapted to be slipped over the offset end of the handle to retain the parts in proper position. Each of the blocks is provided with an eccentrically arranged opening adapted to receive the end of the brace, the end of the brace being arranged at right angles to the body portion as at 19. A cotter pin 20 is arranged in an opening in the end 19 of the brace to retain it in position. Referring to Fig. 3 of the drawings, it will be apparent that when the handle 16 is revolved through an arc of 180 degrees, the eccentric opening in the block 15 will be disposed on the opposite side of the center thereby loosening the brace and permitting removal of the various parts.

Referring to Figs. 5 to 7 of the drawings, the construction therein shown is substantially the same as the construction heretofore described, except that the body portion 1 of the fitting is not provided with the longitudinal opening. In this form of the invention, the leg sections 2 and 3 are adapted to be slid in place and retained by the weight of the other portions of the derrick. As shown, the body portion is provided with a centrally arranged transverse plate 21. The fitting rests upon the lower leg section 3 through the provision of plate 21 and the upper leg section rests upon the fitting.

Referring to Figs. 8 to 12 of the drawings, I have therein shown a further modification of the means for securing the legs and girths in position. As shown, the body portion 1 is provided with the circumferential projection 22 on which the upper leg section 2 rests. The lower leg section supports the fitting and the upper leg section through the provision of the projection 22 is supported

on the fitting. The leg sections are secured in place by means of U-bolts 23 arranged in openings in the body portion. The body portion is provided with flattened portions 24 having openings 25 through which the ends of the U-bolt passes. Nuts 26 are arranged on the ends of the bolts.

In this form of the invention, the sockets 10 which receive the girths are not employed. In place of the sockets, the means for securing the girths in position consists of a pair of lugs 27 arranged on each of the plates 8 and 9. These lugs are arranged in alinement with a substantially semi-circular depression 28 formed in a flange 29 on the ends of the plates 8 and 9. After the girth has been placed in position between the two lugs 27 and in the depression 28, it is retained by means of a U-bolt 30, the ends of which pass through openings in the plates and are provided with nuts 31.

In the use of the form of the invention shown in Figs. 1 to 4 of the drawings, the leg sections may be placed in the body portion of the fitting by loosening nuts 7. It is important to note that it is unnecessary to remove the bolts 6 when the leg sections are to be placed in position or removed. By merely loosening the nuts, the body portion may be loosened from the legs to permit removal. The girths 11 are inserted in the sockets 10 and the ends of the braces are secured in position. The immovable end 13 of the brace is first secured in position and the other end 19 is then placed in the opening in the circular block 15, the circular block being positioned in the opposite position to that shown in Fig. 3 of the drawings.

After the ends of the braces have been secured, the block is rotated by means of handle 16 to tighten the parts and the ring 18 is slipped into position.

In the form of the invention shown in Figs. 5 to 7 of the drawings, there are no nuts or bolts to be loosened or removed when the derrick is erected or disassembled. The derrick is, of course, assembled from the ground upwardly and disassembled from the top. It will be apparent that the upper leg section 2 may be first removed and the braces disconnected. After the braces have been disconnected, the girths may be removed from the sockets 10 and the fitting removed from the lower leg section.

In the form of the invention shown in Figs. 8 to 12 of the drawings, the girths may be removed by loosening nuts 31 on U-bolts 30 and the leg sections may be removed by loosening nuts 26 on U-bolts 23. In either case, it is unnecessary to entirely remove the nuts and bolts, as the bolts do not pass through the legs or girths.

As stated, the provision of the slight adjustment in the diagonal braces permits the derrick to be quickly assembled and then

tightened. The adjustment of the assembled parts does not, in any way, depend upon the rig builder and a symmetrical structure is always obtained. The parts 5 being properly cut in manufacture and the openings properly placed, it is impossible for the derrick rigger to assemble the derrick to produce an unsymmetrical structure.

It is to be understood that while I have 10 described the preferred embodiments of my invention, various changes in the shape, size, and arrangement of parts may be resorted to without departing from the spirit of the invention or the scope of the sub- 15 joined claims.

Having thus described my invention, I claim:

1. A derrick fitting comprising a body portion including a substantially cylindrical portion adapted to receive upper and lower leg sections, said body portion being provided with an opening, a rotatable member mounted in said opening and provided with an eccentric opening for the reception 20 of an end of a brace member, and means connected between said rotatable member and the brace to prevent rotation of said rotatable member.

2. A derrick fitting comprising a body

portion including a cylindrical portion 30 adapted to receive the ends of upper and lower leg sections, said body portion being provided with an opening, a rotatable member mounted in said opening and provided with an eccentric opening to receive an 35 end of a brace member, a handle carried by said rotatable member, and means connected between said handle and the brace to prevent rotation of said rotatable member.

3. A derrick fitting comprising a body 40 portion including a cylindrical portion adapted to receive the ends of upper and lower leg sections, said body portion being provided with an opening, a rotatable member mounted in said opening and provided 45 with an eccentric opening to receive an end of a brace member, a handle carried by said rotatable member and a ring slidable upon the brace and adapted to receive the end of said handle to prevent rotation of said 50 rotatable member.

In testimony whereof I affix my signature in presence of two witnesses.

RICHARD RALPH BLOSS.
